UNITED STATES PATENT OFFICE.

WILLIAM H. SAWYER, OF PROVIDENCE, RHODE ISLAND.

TELEPHONE CENTRAL-OFFICE APPARATUS.

SPECIFICATION forming part of Letters Patent No. 246,218, dated August 23, 1881.

Application filed June 21, 1881. (No model.)

To all whom it may concern:

Be it known that I, WILLIAM H. SAWYER, a citizen of the United States, residing at Providence, in the county of Providence and State 5 of Rhode Island, have invented certain new and useful Improvements in Telephone Central-Office Apparatus; and I do hereby declare the following to be a full, clear, and exact description of the invention, such as will 10 enable others skilled in the art to which it app pertains to make and use the same, reference being had to the accompanying drawings, and to letters or figures of reference marked thereon, which form a part of this specification.

15 This invention relates to means of communication between the desks or tables of a telephone-exchange of a central office, whereby the different operators may give instructions to one another in regard to making connections between subscribers' circuit terminating at different tables or desks.

Heretofore when an operator received at his desk or table a call from a subscriber who wished to be placed in communication with a 25 subscriber on a line terminating at some other table the operator would make the necessary arrangements at his own table, and then write upon a card the letter or number of his table, the number of the subscriber calling, the number 30 of the subscriber called, and the number of the plug-strip upon which he had arranged for making the connection. This card he would send by a boy to the operator at the table at which terminated the line or circuit 35 of the subscriber called. The operator receiving the card would then make the necessary connections, cancel the card, and return it to the first operator, to inform him that the connection had been made. The first operator 40 would retain the cards thus returned to him until some designated time, when he would return them in to the book-keeper, who would make his entries therefrom. In this system there was a great deal of trouble in securing 45 the services of the boys when wanted, and more or less confusion, resulting from the necessary talking in giving them instructions, and from the noise of the walking back and forth, the supply of cards constantly required 50 replenishing, and the book-keeper was sometimes greatly hurried with his work by receiv-

ing a very considerable number of cards, while at other times he was idle while the cards would be accumulating at the several tables, as it was found impracticable for the operators to turn them in singly. 55

The object of my invention is to obviate all these difficulties and inconveniences; and to this end it consists, generally, in providing a central telephone-exchange office with a table, 60 which I denominate a "clearing-table," and connecting all the terminal desks or tables with this clearing-table by a large tube with branches or by separate tubes having such an inclination that a ball placed therein at one of 65 the terminal desks or tables will roll therefrom to the clearing-table, while from said clearing-table there leads a separate tube to each of the line-terminal tables, and having such an inclination that balls will roll therein 70 from the clearing-table to the line-tables. These balls are provided with properly-arranged flat faces, which will not interfere with their rolling, and upon which may be inscribed similar information to that transmitted by 75 means of the cards, as hereinbefore described. An operator at a given table, on receiving a call, will inscribe the proper information upon the faces of the ball and place it in the tube leading from his table on a downward inclination 80 to the clearing-table, where it will be received by an attendant, who will place it in that tube leading downwardly from the clearing-table to the line-terminal table, where the desired connection is to be made. The operator 85 receiving the ball from the clearing-table makes the necessary connections, cancels the ball by marking across its faces, and then places it in the tube leading downward to the clearing-table, where the attendant receiving 90 it and seeing the marks upon it hands it to the book-keeper, who may be seated at the same table. The book-keeper makes the necessary 95 entries, clears off the numbers from the faces of the ball, and returns it through the proper tube to the line-terminal table, from whence it originally came, ready for use again. The whole operation is performed with great rapidity without the necessity of a single step upon the floor or the utterance of a single word. 100 Each of the line-terminal tables should be supplied with a number of balls having the

letter or other designating-mark of the table permanently inscribed thereon, or the balls of the several tables may have different colors. The balls may be made of slate or a similar substance, and the inscriptions made thereon with an ordinary slate-pencil; or the balls may be made of ivory or a suitable composition, and the inscriptions made with an ordinary lead-pencil.

In the accompanying drawings, Figure 1 is a perspective view of four line-terminal tables and a clearing-table connected with tubes, according to my invention. Fig. 2 is a reduced plan view of the same. Fig. 3 is an enlarged view of one of the balls.

The letters A, B, C, and D respectively designate the line-terminal table.

E is the clearing-table, having a back board, f, and provided at about the center of its top with a trough, g, having in its bottom indentations for holding steady the balls which arrive therein.

The letter H designates a main tube terminating over the inner end of the trough and leading upwardly on a proper inclination between the tables A and B, and terminating at its upper end between the tables C and D. From this pipe lateral branches h' h² h³ h⁴ extend obliquely across the end walls of the several terminal tables, terminating at or near the front edges of said walls at points a little above the line of the main pipe, so that said branches incline downwardly to the said main pipe. A pipe, I, inclines downwardly from a funnel, i, supported in the back board, f, of the clearing-table, and terminates in branch i', leading obliquely downward across the end board or table, A, this branch i' terminating immediately over a box, n, arranged upon the table to receive the balls from the pipe. A pipe, K, leads from a funnel, k, to the table B, and longer pipes L and M lead from funnels l and m, respectively, to the tables C and D, where they join with downwardly-inclined branches l' and m', terminating over boxes n, the same as at table A.

The letter O designates the boxes which hold the supply of balls for use at each table.

In the enlarged view, Fig. 3, the letter P designates one of the balls which form the medium of communication through the tubes. This ball is provided with four flat faces, one of which, p, bears permanently the designating-mark of one of the line-terminal tables—for instance, the letter A—and the others, p', are to receive the inscriptions of the information which the operator at table A desires to communicate to the operator at another table in relation to making connections. These inscriptions also serve as memoranda, from which the book-keeper can make his charges against the several subscribers.

The operation of my invention is as follows: Let us suppose that the operator at table A has received a call from Station No. 25 on a line terminating at his table, and that this subscriber has signified that he wishes to be placed

in communication with a subscriber, 175, who is on a line which terminates at table D. The operator takes from his box O one of the balls, 70 and on the vacant face p', next below the letter of the table A, inscribes the number, 25, which is the number of the station calling, and on the face next below this he inscribes the number 175, which is the number of the station with 75 which he desires Station No. 25 to be connected. On the last face p' he inscribes the number of the plug-strip upon which he has arranged that the connection shall be made—say 2, as shown in Fig. 3. The ball being thus inscribed, 80 the operator places it in the mouth of the branch pipe h', through which it rolls to the main pipe H, which discharges it in trough g. Immediately on its arrival the attendant at the clearing-table seizes it and observes, as is his duty, the 85 middle one of the faces p'. This face he finds inscribed with the number 175, and knowing that to be the number of a station on a line terminating at table D, he immediately places the ball in the funnel m, whence it rolls into 90 pipe M, and is conveyed by it to table D, being discharged through the branch m' into the box n at that table. The operator at table D hearing the ball fall seizes it, and finding the number 175 inscribed thereon, he calls up subscriber 175, and on receiving an answer from him inserts the necessary plug in strip 2 to connect the line on which the subscriber is located with the line on which the Subscriber No. 25 is located. This being done, he crosses 95 over the faces of the ball, as shown in dotted lines, Fig. 3, places the ball in the branch tube h⁴, through which it passes to main tube H, which carries it back to the clearing-table. The attendant at the clearing-table receiving 100 the ball, and seeing it crossed hands it to the book-keeper, who makes his entries, effaces the inscriptions on the faces p', and returns the ball through tube I to table A, from whence it came originally. 110

It is obvious that instead of using a main tube, H, with lateral branches, I may use a separate tube for conveying the balls from each of the line-terminal tables to the clearing-table; and, further, instead of running the tubes to 115 and from the clearing-tables to the line-terminal tables, I may arrange tubes to lead directly from one line-terminal table to another. In this case three tubes would lead on downward inclinations from each table, and terminate at 120 the other three tables, respectively, so that each table would have three outgoing and three incoming tables, the manner of using such an arrangement of tubes being obvious.

Having now thus described my invention 125 and explained the operation thereof, what I claim is—

1. In a telephone central station, the combination, with several line-terminal tables or desks, of inclined tubes arranged to convey 130 balls, substantially as described, from each table to the others, for the purpose set forth.

2. The combination, with the line-terminal tables and the clearing-table, of pipes leading

on a downward inclination from each line-terminal table to the clearing-table, and other pipes leading from the clearing-table on downward inclination to each of the line-terminal tables.

5 3. The combination, with the line-terminal tables and the clearing-table, having pipes leading therefrom separately downward to each of said line-terminal tables, of the main pipe to H, inclined downwardly to the clearing-table,

and having the lateral branches leading to the several line-terminal tables, substantially as described.

In testimony whereof I affix my signature in presence of two witnesses.

WILLIAM H. SAWYER.
